United States Patent Office

Des. 175,649
Patented Sept. 20, 1955

175,649

PLASTIC BOTTLE

John V. Ryden, Mount Vernon, N. Y., assignor to Vick Chemical Company, New York, N. Y., a corporation of Delaware

Application February 10, 1955, Serial No. 34,447

Term of patent 14 years

(Cl. D58—8)

FIG.3

FIG.1

FIG.2

FIG.4

Fig. 1 is a front elevational view of a plastic bottle showing my new design;

Fig. 2 is a side elevational view thereof;

Fig. 3 is a top plan view thereof; and

Fig. 4 is a bottom view thereof.

The plastic bottle is shaded to indicate contrast in color.
I claim:

The ornamental design for a plastic bottle, as shown and described.
